UNITED STATES PATENT OFFICE

2,563,025

AUXILIARY TURBINE AND PUMP FOR
COMBUSTION CHAMBERS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application March 11, 1947, Serial No. 733,824

1 Claim. (CL 60—35.6)

1

This invention relates to combustion chambers adapted for propulsion and having a rearward discharge nozzle.

It is the general object of this invention to provide an improved construction in which a portion of the gases discharged from the combustion chamber are utilized to drive an auxiliary turbine and one or more centrifugal pumps or other devices associated therewith. These pumps may act as feed pumps for the combustion chamber or may be used for other desired purposes.

To the accomplishment of this general object, an auxiliary turbine is rotatably mounted on the discharge nozzle for coaxial rotation relative thereto and is provided with an annular series of turbine blades. Each of these blades projects radially inward for engagement by the gas stream, but only in the outer and cooler peripheral portion thereof.

The invention further relates to arrangements and combinations of parts which will be herein-after described and more particularly pointed out in the appended claim.

A preferred form of the invention is shown in the drawing, in which

Fig. 1 is a sectional plan view of a portion of a discharge nozzle having this invention associated therewith;

Fig. 2 is an end view of the auxiliary turbine, looking in the direction of the arrow 2 in Fig. 1;

Fig. 3 is a transverse sectional elevation through one of the pumps and taken along the line 3—3 in Fig. 1; and

Fig. 4 is a fragmentary plan view, looking in the direction of the arrow 4 in Fig. 2.

Referring to Fig. 1, a portion of the discharge nozzle N of a combustion chamber is shown in section, together with centrifugal pumps P and P' and an auxiliary turbine T.

Each pump includes an impeller comprising 40 curved blades 10 (Fig. 3) mounted on a ring or sleeve 11. The sleeve 11 is supported by anti-friction bearings 14 (Fig. 1), which in turn are supported by the fixed nozzle N.

A casing 16 encloses the impellers 10 and may be secured to the nozzle N by clamping bolts 17. For convenience in assembling, the casing 16 may be made in two parts, secured together by bolts 19.

Feed pipes 18 supply the liquids to be pumped, and the liquids are delivered through volutes 20

2

(Fig. 3) to discharge pipes 21. The liquids supplied through the pipes 18 and delivered through the discharge pipes 21 may be used for any desired purposes.

5 The sleeve 11 is extended beyond the nozzle N and supports the turbine T, which comprises a plurality of curved blades 30, the inner ends of which project a short distance radially inward beyond the rear edge of the nozzle N.

The blades 30 are engaged by the outer portion of the stream of discharging combustion gases and the turbine is thus rotated to provide power for the pumps P and P' or for any other purpose.

As all of the blades 30 are at all times engaged 15 by the gas stream and accordingly are at all times active, only the extreme outer or peripheral portion of the gas stream need be utilized. This outer portion is the coolest portion of the gas stream and also travels at the slowest speed, both

20 being items of distinct advantage.

If the pumps P and P' are used to feed combustion liquids to the associated combustion chamber, it is necessary to provide means for starting the pumps before the chamber is in operation, and for this purpose an outer series of blades 40 is provided, to which compressed air may be supplied through one or more nozzles 41. This use of compressed air is required only until the combustion chamber is in effective operation 25 and only until combustion gases are being discharged in substantial volume through the nozzle N.

The pumps P and P' may obviously be used for other purposes than feeding combustion liquids 30 to an associated chamber, and other devices besides centrifugal pumps may receive power from the rotated sleeve 11.

Having thus described the invention and the advantages thereof, it will be understood that the invention is not to be limited to the details herein disclosed, otherwise than as set forth in the claim, but what is claimed is:

In combustion apparatus having a non-rotated discharge nozzle for combustion gases, in combination, a cylindrical sleeve mounted to rotate freely on said nozzle and having a portion extending outward beyond said nozzle, bearings for said sleeve on said non-rotated nozzle, a plurality of turbine blades internally mounted on said outwardly extending portion and projecting a rela-

tively short distance only within the outer end of said nozzle and into the gas stream, a centrifugal feed pump having a casing mounted on said non-rotated nozzle and secured thereto, an impeller for said pump mounted on said rotating sleeve and within said non-rotated nozzle, and supply and discharge connections to said pump casing.

ESTHER C. GODDARD,
Executrix of the Last Will and Testament of 10
Robert H. Goddard, Deceased.
